UNITED STATES PATENT OFFICE.

FRANK M. SLOUGH, OF ELYRIA, OHIO, ASSIGNOR TO LAMARTINE BROOKS FAY, OF ELYRIA, OHIO.

SHOE HEEL.

Application filed December 9, 1920. Serial No. 429,420.

To all whom it may concern:

Be it known that I, FRANK M. SLOUGH, a citizen of the United States, residing at Elyria, county of Lorain, and State of Ohio, 5 have invented certain new and useful Improvements in Shoe Heels; and I do hereby declare the following to be a full, clear, concise, and exact description, as will enable others skilled in the art to which my invention 10 appertains to make and use the same.

My invention relates to shoe heels, and particularly to that type of shoe heels wherein an intermediate portion between the bottom or tread end of the heel and the top 15 or attaching end, is of relatively small cross sectional area; my invention relates in some of its phases, to metallic shoe heels and an improved method of making the same, although in other of its phases, my invention 20 is not confined to metallic shoe heels, and also is not confined to any particular method of manufacture.

It has been the practice to make ladies' 25 shoe heels, particularly of the "French" type, of metal, the same being cast by a die casting process or otherwise, and in such heels the attaching nails whereby the heels are secured to the bottom of a shoe, are cast integrally with the heel proper with their 30 points projecting upwardly therefrom. The cobbler or other workman attaching such heels to shoes, drives or forces the heel and shoe together, to cause the nails to enter the bottom of the shoe and the nails are 35 generally clinched over at their ends so as to lock the heel securely into position. Sometimes, however, during this process, the nails become bent or broken or become loosened from the metal wherein they are 40 cast, and the heels containing such defective nails, as the case may be, are useless and must be junked, or else due to an imperfect connection between the shoe and the shoe heel, the wearer will become dissatisfied.

45 It is an object of my invention to eliminate the necessity of providing a means whereby nails may be replaced within the heel whenever this is desirable. It is a further object of my invention to construct a metallic shoe 50 heel of the type mentioned, in a new and useful manner; it is a further object of my invention to provide a shoe heel which may be removed from a shoe to which it has been secured by the nails whose ends may be 55 clinched without removing the nails there-

from. This last mentioned object, being accomplished, enables the shoe repairman to remove heels from shoes which have been discolored or marred in various ways, and refinish the exterior of said heels by enamel- 60 ing or by other suitable process.

It is a further object of my invention to provide a shoe heel which may be made of steel, brass or other metal instead of aluminum, thus enabling the shoe heels to be 65 electro-plated or be subjected to other finishing processes which are not as successful in the case of aluminum heels. One of these processes which I have in mind and which may attend the use of steel in shoe heels, 70 in the sheet metal-article manufacturing arts, as the Parker process, which gives steel a black finish which penetrates into the steel to a considerable depth and which is not readily marred by scratching. 75

It is a further object of my invention to provide an independent supporting means which may also be made of steel in whole or in part, thus enabling one to electrically 80 weld the heads of the nails to the supporting means, and thereby obviating the necessity of casting the nails into such a metal as aluminum, as is the present practice, thus securing a better joint between the nail heads and the support, in a less expensive 85 way.

A further object of my invention is to provide a new nail supporting means which may be utilized in heels as at present manufactured, so as to utilize heels from which 90 the nails have been broken or in which the connection between the nails and the heels, has become faulty.

Another object of my invention is to enable a heel tread, such as a leather or rubber 95 heel tread, to be secured to the bottom of the heel by securing it to the nail-supporting means above mentioned.

Other objects of my invention and the invention itself will become apparent to those skilled in the art, by reference to the following description, and to the accompanying drawings, which form a part of the specification.

100 Referring to the drawings: Fig. 1 shows a vertical cross-sectional view 105 of a shoe heel embodying my invention. In this figure an interior view is had, showing the nail-supporting means and the method of securing the nail-supporting means to 110

the heel, as well as the method of attaching the tread of the heel thereto, also in cross-section.

Fig. 2 shows a plan view of the heel of Fig. 1.

Fig. 3 shows a plan view, taken from below, of a securing cup, located in the tread end of the shoe heel of my invention, with the leather filling and rubber tread lift removed therefrom, to enable one to see the interior construction.

Fig. 4 shows a vertical sectional view of the said securing cup.

Referring now to the drawings, in all of which like parts are designated by like reference characters, at 2 I show the shell, made preferably of thin, soft steel stock, and at 3 I show a nail-supporting means, which is substantially of the shape of an inverted cone having a threaded opening at the lower end or apex thereof, whereby a screw 5 may be secured to the said inverted cone. This cone is preferably constructed of sheet steel in the form of web, the said web having a rim portion 21 and arms 11 extending from the said rim portion downwardly to the apex of the cone, where there is provided a threaded opening to admit the machine screw 5. The arms 11 are preferably stiffened by having longitudinal ribs extending radially from the said screw opening. Flanges 7 are provided from the said rim portion, preferably extending inwardly to support the nails 6 placed head downwards upon the said flanges.

Prior to insertion of the said inverted cone member into the heel shell, the nails are secured to the flanges, preferably by being electrically spot-welded to the flanges, or in any other suitable way. The contour of the outer surface of the inverted cone is generally of that shape to make it fit snugly within the inner walls of the upper portion of the heel shell 2.

Located in the lower portion of the heel shell I provide an inverted cup member 4 having an opening 17 in the end wall or roof thereof, and which opening is adapted to permit the passage of the screw 5, whereby the said inverted cup member and the said inverted cone member may be secured together with their perforated ends towards each other. A plurality of openings 22 are made in the side walls of the inverted cup member to cause it to be lighter than it otherwise would be, and still maintain sufficient thickness to make it stiff. The said cup member has its outer surface formed of such a shape as to fit snugly against the inner walls of the bottom of the heel shell 2, and when the screw 5 is turned up tightly with its end passing through the opening in the bottom of the inverted cone member 3, the two members 3 and 4 will be maintained a certain distance apart by the converging

walls of the shoe heel shell, and the screw 5 will tightly hold in fixed positions relative to each other the shell 2, the inverted cone member 3 and the inverted cup member 4.

The inverted cup member 4 is provided with a pair of lips 15 at its sides and a lip 16 at its rear and near the mouth of the inverted cup, and which lips before the assembly of the heel structure stand vertically in the position substantially as illustrated in Fig. 4, but when the workman prepares the heel structure for service, he will, after the three principal parts of the heel have been bolted together by the screw 5, drop into the mouth of the cup member 4 leather lifts or fillers to nearly fill the said cup member, and then will bend over the lips 15 and 16 to securely hold the said leather fillers in place. A rubber or leather heel lift 12 may then be nailed on to the bottom of the heel structure by nails, such as 13, passing from the said lift into the leather fillers 14. When this is accomplished, the heel is ready for attachment to the shoe, and is attached to the bottom of a shoe in the usual manner by forcing the nails 6 through the said shoe bottom, therein they may be clinched or secured in any other desired way. If desired, the nails 6 may be replaced by bolts, but it is my belief that nails are preferable.

Whenever it is desired to remove the heel from the shoe, this may be accomplished in the heel structure of my invention by removing the rubber or leather lift 12, straightening the lips 15 and 16 so that the leather lifts or fillers 14 will drop out of the cup 4, and then the screw 5 will be backed off until the cup 4 is released from the inverted cone 3, whereupon the shell 2 may be completely removed from the heel, the inverted cone, however, still being secured to the heel by the nails 6. The heel shell 2 may then be repaired or re-enamed, or re-finished in any suitable way, as may be desired, and re-attached to the cone member 3, and thereby to the shoe, by inverting the order of the processes described for taking the heel shell from the shoe.

My invention, in so far as it relates to the use of the cone-shaped member 3 which supports the nails 6 may be applied to heels which are now in use and which have been rendered unfit for use by the attaching nails which project from the upper part of such heels being broken or dislocated from the said heels. Such heels as are now commonly in use have a plurality of ledges which are integral with the shell of the heel, and which shell is commonly composed of cast aluminum and the nails project from the said ledges, being secured therein by their heads. The securing of such nails to such heels is accomplished by casting the nail heads within said ledges when the heel shell is manufactured by the casting process.

Such heel shells when the nails become broken or dislocated from their sockets within the said ledges are now commonly thrown away, and a great loss ensues. By 5 the use of my novel inverted cone-shaped member, which supports the nails 6 in the manner before described, I am enabled to take such heels, and by making the cone-shaped member of such outer contour as will 10 enable it to fit around said ledges and by arranging the ears or flanges 7 so that they will preferably occur at other points adjacent the periphery of the heel than at the ledges, such heels of the prior art may be 15 again fully equipped with nails and used. When so used, I may employ a member corresponding to the cup-shaped member 4, or where the prior art heels are solid at their necks, rather than having an opening there- 20 through, a hole through such solid portion can be used instead of the opening 17 of a special cup-shaped member, as 4. Also in the case of some of the prior art heels I may secure to such a solid portion, located 25 by the neck, the inverted cup-shaped member 4 having lips 15 and 16, and by the use of such lips secure a filler 14, as before described, and enable a tread, such as 12, to be attached to the bottom of such prior art 30 heels, as described in connection with my own improved heel.

From the foregoing, it is apparent that my invention has a number of phases, some of which may operate independently of the 25 others. It has heretofore been considered impractical to form a shoe heel shell of the shape commonly employed for French heels constructed of drawn sheet steel, since if the steel were made thick enough, so 40 that it could be drawn as much as would be necessary to provide the material at the bottom portion of the said shell, it would be too heavy, and if the sheet were made thin enough, so as to be satisfactory for 45 use, the metal would rupture when drawn down, to complete the forming of the bottom of the shoe heel.

In connection with my invention I have evolved a method of manufacturing such a 50 shoe heel of thin, soft, drawn steel, whereby when finished the same can be made as light, or lighter than, the aluminum heels now in use, and will be stronger than such heels. This will be so, even when the 55 weight of the interior parts of both types of heels is considered, especially since the inverted cone member 3 and the inverted cup member 4 are so disposed and shaped as to reinforce the outer heel shell 2.

60 I accomplish the drawing of the steel shell by making it in two pieces, the first piece being stamped from a steel flat sheet and then drawn downwardly in the usual way to form a cup member having an open- 65 ing at the bottom, the said cup member ex-

tending down to the points marked 8 on the drawing of Fig. 1. I then form that portion of the shell below the points 8 from a cylindrical tube of soft, drawn steel and expanding and swaging the tube to form 70 the flared mouth and the straight side edge 28, respectively. Then by placing the upper and lower portions of the heel each on a jaw of an electric welding machine and bringing the jaws together, the heat de- 75 veloped by the electric contact between the upper and lower portion of the heel shell joining at the points 8 will fuse the steel shell and weld the two parts together.

If desired, the lower portion of the heel 80 shell 2, which I have described as being made from a cylinder of soft, drawn steel, can be made from a flat piece of steel pressed downwardly to form a cup with an opening in the bottom, but I consider it 85 preferable to manufacture the lower portion of the heel from a cylinder, as fewer failures will occur, due to rupturing of the material. Of course, the drawing processes above described will be accomplished in the 90 best known ways and may be done in a number of operations with intervening annealing of the sheet metal operated upon between drawing operations. The electric welding of the two parts to join them together may also be accomplished in various ways, which would be the equivalent 95 of that described herein.

After the electric welding process has been accomplished, the joint at 8-8 be- 100 tween the upper and lower parts of the shell 2, by grinding can be smoothed, so that it will not be visible after the heel shell has been given a finish.

Such a heel shell is preferable to that of 105 aluminum for a number of reasons, among them being strength, durability, economy, lightness and the ability to take a finish on its outer surfaces which will not be subject to removal by coming in contact with extra- 110 neous objects.

I prefer, for some purposes, to give the 115 steel heel shell, as above constructed, or constructed in any equivalent way, a finish by what is commonly known in the art as the Parker process. I find that heels so finished, when scratched, do not show the effects of such scratching, since the material of the metal is colored to some considerable depth. The interior parts of the heel, such as the 120 cone 3 and the cup 4, may be similarly finished, to prevent it from rusting, or may remain unfinished, or may be electrically plated, such as copper-plated, if desired.

Having thus described my invention, I 125 wish it to be understood that numerous and extensive departures may be made from the embodiment herein illustrated and described for the purpose of explaining the invention, but without departing from the spirit there- 130

of. Also, the methods employed may be varied somewhat to accomplish the same results in substantially the same way, all of which I consider within the purview of my invention.

What I claim is:

1. In a French heel for ladies' shoes, in combination with an exterior shell composed of relatively thin steel, the said steel shell comprising upper and lower portions joined together at a heel neck or intermediate portion of reduced horizontal cross sectional area, a pair of bracing elements within the said thin steel shell to strengthen the same, one of the said elements being located in the upper portion of the steel shell, the other element being within the lower portion of the said steel shell, the outer surfaces of the said elements conforming generally in shape so as to contact with the inner contacting surfaces of the said shell, the said elements being secured together at their adjacent ends, a plurality of nails mounted onto the upper limit of the said upper element by having their heads secured to the said rim, the said heel being adapted to be secured to the bottom of a shoe by the said nails,

by forcing the entire aforesaid heel structure combination onto the said shoe sole bottom, said nails entering said sole and adapted to be clinched therein.

2. In a "French" type shoe heel, in combination with an outer shell having a recess in its lower tread surface, an inverted cup member adapted to be placed in the said recess, the said cup member being preferably constructed of a material such as soft steel, lips extending from the side walls near the mouth of the said cup, a wearing tread for the said heel having a portion extending into the said recess, the said portion being united to the main body of the said wearing tread by a neck portion of reduced horizontal cross sectional area, and the said tread being adapted to be secured to the said cup by turning over the said lips over the shoulder resulting from the said recess, and means to secure the said cup within the said heel recessed portion.

In witness whereof, I have hereunto signed my name this 4th day of December, 1920.

FRANK M. SLOUGH.
